UNITED STATES PATENT OFFICE

116,746

DESIGN FOR A CONTROL UNIT FOR A RADIO RECEIVER

Richard C. Marholz, Chicago, Ill., assignor to Belmont Radio Corporation, Chicago, Ill., a corporation of Illinois

Application March 30, 1939, Serial No. 83,936

Term of patent 7 years

To all whom it may concern:

Be it known that I, Richard C. Marholz, a citizen of the United States, residing at Chicago, in the county of Cook and State of Illinois, have invented a new, original, and ornamental Design for a Control Unit for a Radio Receiver, of which the following is a specification, reference being had to the accompanying drawing, forming part thereof, in which:

Figure 1 is a front perspective view of a control unit for a radio receiver showing my new design;

Figure 2 is a front elevational view thereof. The characteristic features of my design are shown in solid lines in the drawing.

I claim:

The ornamental design for a control unit for a radio receiver, substantially as shown and described.

RICHARD C. MARHOLZ.
